Joseph P. Manton

UNITED STATES PATENT OFFICE.

JOSEPH P. MANTON, OF PROVIDENCE, RHODE ISLAND, ASSIGNOR TO
EDGARTON BYNNER, OF BROOKLYN, NEW YORK.

SHIP-WINDLASS.

SPECIFICATION forming part of Letters Patent No. 350,462, dated October 5, 1886.

Application filed January 15, 1885. Serial No. 152,961. (No model.)

To all whom it may concern:

Be it known that I, JOSEPH P. MANTON, a citizen of the United States, residing at Providence, in the county of Providence and State 5 of Rhode Island, have invented certain new and useful Improvements in Ship-Windlasses; and I do hereby declare the following to be a full, clear, and exact description of the invention, such as will enable others skilled in 10 the art to which it appertains to make and use the same, reference being had to the accompanying drawings, and to letters or figures of reference marked thereon, which form a part of this specification.

15 My present invention relates to improvements in windlasses for ships' use; and it consists, essentially, first, in providing the main shaft of the windlass, carrying one or more wild-cats, with a worm gear-wheel connected 20 thereto for driving the windlass, said screw-gear engaging a screw or worm secured to a fore-and-aft driving-shaft, which in turn is driven by a donkey-engine or other suitable motor located considerably abaft the windlass.

25 The invention consists, secondly, of a ratchet-wheel firmly secured to the windlass-shaft, in combination with a recessed worm-gear carrying spring-actuated pawls adapted to engage said ratchet, the gear being loosely mounted 30 upon the shaft, whereby the power from the worm is transmitted to the gear and pawls, and from the latter to the ratchet, thus causing the shaft to revolve in one continuous direction, all as will be more fully hereinafter set forth.

35 Heretofore windlasses or machines of this class have had the worm-gear keyed firmly to the main shaft, or when loosely mounted thereon the gear is connected to a head secured to the shaft by means of removable block-keys. 40 These devices, however, admit of the windlass being revolved in both directions, the latter device necessitating the removal of block-keys, in order to operate the windlass by manual power, whereas the windlass, if provided with 45 my invention, is always ready to be worked either by steam or hand power without change.

In the accompanying sheet of drawings, Figure 1 represents an end elevation of a pump-brake windlass embodying my invention, the 50 steam-power being furnished by means of a donkey-engine and boiler placed in a house located abaft the windlass, as viewed from the

port side. Fig. 2 is a partial plan view of the same, the house being shown in horizontal section. Fig. 3 is a rear elevation, enlarged, of a portion of the windlass, showing in section the worm-gear, ratchet, and port wild-cat; and Fig. 4 is a partial transverse section of the screw-gear, showing the method of its attachment to the ratchet, the latter being secured 60 to the windlass-shaft.

The following is a description of the invention, including the manner of its operation.

A, again referring to the drawings, designates one or more steam-engines, which by 65 means of shafts c^2 c^3 and gearing c^4 connects with the fore-and-aft inclined shaft C, carrying the worm E' at its forward end, said shaft, when necessary, being formed in two or more pieces and connected together by means of 70 couplings c^5 .

t' designates thrust-bearings for the worm and its shaft, as common.

R designates the main or windlass shaft, carrying loosely-mounted wild-cats K, and pump-brake mechanism for operating the windlass 75 by hand-power, also as common.

(I have represented portions of a pump-brake windlass in the drawings; but, obviously, the windlass may as readily be connected with 80 a vertical shaft and capstan or other type of windlass, if desired.)

T represents the side bits, provided with boxes t' , which support the windlass-shaft.

F represents a ratchet-wheel rigidly secured 85 to the shaft R, and E designates a worm-gear loosely mounted upon said shaft, adapted to engage the worm E'.

p' represents pins secured to the rim of the gear E, each carrying a pawl, p , which in turn 90 engage teeth f of the wheel F. Springs s insure the working of the pawls.

The worm-wheel E consists of two parts—that is to say, one side thereof is made removable or detachable, as shown at e , for the 95 purpose of receiving and inclosing the ratchet-wheel F, before described. The side e is secured to the body portion of the worm-wheel, and is provided with a hub, through which the main shaft R loosely passes, the 100 whole, when combined with the ratchet and pawls, producing a very compact arrangement, as clearly shown in Figs. 3 and 4.

The operation is as follows: The engines A

- are first started, which, by means of intermediate gearing, causes the shaft C to revolve in the arrow-direction, the worm E' at the same time, by means of its engagement with the gear-wheel E, causing the latter to revolve in its arrow-direction, said gear now, by its pawls *p* and engaging-wheel F, rotating the windlass in the same direction, thereby adapting it to be employed for hoisting anchors or working purposes, as desired. It is obvious that should the worm E' be revolved in the opposite direction the pawls *p* would then slide freely over the teeth *f* of the wheel F, the shaft R remaining stationary.
- When the windlass is operated by manual power from the brakes or capstan, as the case may be, the worm-gear will then remain stationary and the ratchet-wheel F revolve freely therein, thus readily adapting the windlass to be operated by steam or manual power at will without change, other than simply shutting off the steam from the engines. A clutch, *c'*, Fig. 2, adapts the engines to be used for other hoisting purposes and independently of the shaft C.
- Practically it is undesirable to revolve a windlass backward. The ratchet-wheel and loosely-mounted worm-gear attachment herein described therefore adapt the combined steam and hand power windlass to be revolved in one direction only, the attachment being both strong and efficient.
- The gear E, with its connections, may be located between the bits, if desired, instead of being outside thereof, as shown.
- I am well aware that screw-gearing has been used prior to my invention for driving windlasses, and is common; neither is it new to provide the engine-shaft or the intermediate shaft of a combined steam and manual power working windlass with a self-acting clutch,

and therefore I do not claim such construction and combination, broadly; but

What I do claim, and desire to secure by United States Letters Patent, is—

1. In a ship's windlass, the combination, with a ratchet-wheel rigidly secured to the windlass-shaft, of a chambered or hollow worm gear-wheel loosely mounted on said shaft, spring-actuated pawls pivoted to and working in said wheel, a cap or plate removably secured to and forming one side and hub of the worm-wheel, a worm, and means whereby said worm and its wheel are operated, all constructed and arranged substantially as shown and set forth. 55
2. The loosely-mounted hollow gear-wheel having a removable side and spring-actuated pawls pivoted to the interior of said wheel, in combination with a rigidly-secured ratchet-wheel arranged in the gear-wheel and a driving-shaft having said wheels mounted thereon, substantially as set forth. 60
3. In a manual or steam power windlass, the combination, with the windlass having a hollow worm-wheel loosely mounted on the windlass-shaft, a ratchet-wheel secured to the said shaft inside the worm-wheel and connected with the latter by means of self-acting pawls, of a steam-winches or donkey-engine mounted in a housing located abaft the windlass, a suitably-mounted driving-shaft, C, arranged fore-and-aft, having a worm secured thereon engaging said worm-wheel, and gearing whereby the shaft C is actuated at right angles, or nearly so, with the driving-shaft of said donkey-engine, substantially as shown and set forth. 70

In testimony whereof I have affixed my signature in presence of two witnesses.

JOSEPH P. MANTON.
